CLAIM

The ornamental design for a fish hook bottle opener, as shown and described.

DESCRIPTION

FIG. 1 is a perspective view of a fish hook bottle opener;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view therof.

The portion of the drawings shown in broken lines is for illustrative purposes only and forms no part of the claimed design.
